UNITED STATES PATENT OFFICE.

ALEXANDER WINTON, OF LAKewood, OHIO.

MOTOR-STARTING MECHANISM.

1,401,747.

Specification of Letters Patent. Patented Dec. 27, 1921.

Application filed December 23, 1916. Serial No. 138,653.

To all whom it may concern:

Be it known that I, ALEXANDER WINTON, citizen of the United States, residing at Lakewood, in the county of Cuyahoga and State of Ohio, have invented certain new and useful Improvements in Motor-Starting Mechanism, of which the following is a specification.

This invention relates to internal combustion motors and starting mechanism therefor and particularly to starting mechanism of the air type.

In starting internal combustion motors with air it is customary to employ a distributor for distributing air to the several cylinders in proper time so that a starting torque will be transmitted to the motor in the proper manner to start it in the proper direction. When such a device is used it is rendered useless when the direction of rotation of the motor is to be reversed by reason of the improper timing of the distributor by such reverse rotation. The present invention therefore relates to a starting device and particularly distributing mechanism which is easily adjusted so that a reverse starting torque may be transmitted to the motor or in other words so that the motor may be started in either direction.

The invention may be further briefly summarized as consisting in the construction and combination of parts hereinafter set forth in the following drawings, description and claims.

Referring to the drawings Figure 1 is a side elevation of a portion of an internal combustion motor provided with my device; Fig. 2 is a section through the several distributing ports of the distributor head; Fig. 3 is a vertical section; Fig. 4 is a view in plan showing two ports in the valve for determining the direction of air supply; and Fig. 5 is a view showing one of the distributing valves.

In the arrangement shown in the drawings the motor 1 is provided with a shaft 2 which may be the cam shaft or any other shaft properly timed with the crank shaft, and it is to this shaft 2 in the present instance that the distributing mechanism is applied and this mechanism will now be described. The motor is intended to be reversible and may be of the two or four cycle type.

The distributor comprises a main body

portion made up of two portions 3 and 4 the former having conveniently arranged ports 5 each leading to a check valve port 6 near the center of such body portion. 60 These check valve ports 6 are symmetrically arranged about a central opening 6' and each is provided with a seat 7. The portion 4 of the main body portion is in like manner provided with check valve ports 8 65 and a central opening 8' in alignment with the openings 6 and 6' and also provided with valve seats 9. The arrangement of the ports 6 and 8 and their valve seats is such that internal valve chambers are 70 formed each having a valve seat at both ends.

The outer end faces of the two portions 3 and 4 of the main body portion are faced off to form distributing valve seats 10 and 75 11 respectively for the purpose of receiving against them the distributor valves as will appear.

Secured to the main body portion 3 is a distributor valve cover 12 having a distributor valve chamber 13 therein and a stuffing box 14 receiving packing 15 and gland 16 arranged about the shaft 2 to prevent leakage at this point.

Engaging the valve seat 10 is a distributing valve 17 in the form of a disk having an air distributing opening in the form of a segmental slot not shown in this valve but similar to the one shown in the other distributing valve shown in Fig. 5 and described later. This distributing valve 17 has a hollow shank 18 adapted to receive the end of the shaft 2 and loosely keyed thereto by a key 19. A spring 20 is arranged in an opening 21 in the end of the shaft 2 and it 85 engages the bottom of the hollow shank and tends to force the valve 17 upon its seat 10. The hollow shank 18 is provided with an extension extending into the central opening of the body portion 4 and loosely 90 keyed to the hollow shank of the other distributing valve 22. This distributing valve 22 is provided with a segmental port or opening 23, hereinbefore referred to and adapted to pass the several check valve ports 95 10 and distribute starting air to such ports. This distributing valve 22 is held upon its seat 11 by a ball 24 engaged by a spring 25 in a cover plate 26 secured to the body portion 4. This cover plate has an air supply port 27 leading through the same to a valve chamber 28 about the distributing

100

110

valve 22 and another air supply port 29 leading to an air channel 30, shown in dotted lines and extending entirely through both parts of the main body to the opposite cover 12 where it communicates with a conduit 31, shown in dotted lines, passing to the other valve chamber 13. The outer face of this cover is a valve seat and receives a supply valve 32 arranged in a valve chamber 33 formed in a supply casing 34. The supply valve 32 has a hollow shank 35 loosely keyed to a valve stem 36 passing out of the supply casing through a stuffing box consisting of the box 37, the packing 38 and gland 39. The outer end of the valve stem 36 is provided with a hand wheel 40 or other suitable manipulating device. A spring 41 is arranged between the valve 32 and the supply casing and holds the valve upon its seat.

The supply valve 32 is provided with two openings 42 and 43 90° apart and these openings register with the ports 27 and 29 which are substantially 180° apart, according to the position of the valve as determined by the operator.

This supply valve 32 is limited in its movement by a recess in its periphery forming shoulders which engage a stop pin 44 in the cover plate 26.

Air is applied to the casing 34 by a supply pipe 45 leading to any suitable source of compressed air. Branch pipes 46 lead to the several air inlet valve devices 47 connected to the several cylinders and of any preferred construction.

The several check valve chambers formed in the main body are provided with check valves each consisting of a valve proper 48 and oppositely extending guides 49 extending into the check valve ports 6 and 8 and these valves are adapted to seat on either of the valve seats 7 and 9 according to the direction of flow of the starting air supplied to the ports 6 and 8.

In operation the user manipulates the air supply valve so that it is in the correct position for the proper direction of starting when air will pass, for example, through the port 43 and to the distributing valve 22

or through channels 29, 30 and 31 to the valve 17, from whence it will be distributed to the ports 8 in proper time to start the motor the check valves seating to the right as shown in Fig. 3 or to the left, according to the adjustment of the valve 32 and closing the check valve port 6 at its opposite end.

It is obvious from the foregoing that by manipulating the supply valve the motor may be started in either direction.

Having described my invention, I claim:—

1. Starting apparatus for internal combustion motors, comprising a casing having a series of circumferentially spaced cavities each open at both ends and communicating with a motor cylinder, a check valve in each cavity seating toward either end thereof, two valves rotating together in timed relation with the motor and each provided with a port passing in turn the open ends of said cavities, said casing having two chambers containing said rotating valves and a pressure chamber communicating by ports with in the casing with said two chambers, and a single valve in said pressure chamber having two positions in either of which pressure flows to one and is cut off from the other of said two chambers.

2. Starting apparatus for internal combustion motors, comprising a casing having a series of circumferentially spaced cavities each open at both ends and communicating with a motor cylinder, a check valve in each cavity seating toward either end thereof, two valves rotating together in timed relation with the motor and each provided with a port passing in turn the open ends of said cavities, said casing having two chambers containing said rotating valves and a pressure chamber communicating therewith, and a valve in said pressure chamber having two positions in which pressure flows to one or the other of said two chambers, said last named valve having turning movement about the axis of rotation of said rotating valves.

In testimony whereof I affix my signature.

ALEXANDER WINTON.
